COOLING OF GAS TURBINES

George F. Wislicenus, Baltimore, Md., assignor
to Packard Motor Car Company, Detroit, Mich.,
a corporation of Michigan

Application February 12, 1949, Serial No. 76,161

2 Claims. (Cl. 60—39.66)

1

The invention relates generally to engines of the gas turbine type and more particularly to the cooling thereof.

The general object of the invention is to provide a novel structure for conducting cooling air to the turbine portion of such an engine at such pressure or pressures as will permit its eventual discharge into the power stream.

Another object is to provide a novel arrangement of parts permitting the cooling air utilized in the turbine portion of the engine and discharged into the power stream, to be taken from points in the path of the air stream in the engine where the pressures are at the minimum necessary, in view of any additional head imparted thereto, to effect discharge into the power stream.

A further object is to provide an engine structure in which the cooling air is taken at a point where its pressure is at the minimum necessary to effect the desired flow thereof, so that a minimum of energy is thereby expended upon it.

Still another object is to provide an engine structure in which the cooling air utilized in different parts of the engine may be taken from the air stream at different pressure levels, determined by the pressures necessary to effect its discharge and by any additional head imparted thereto after withdrawal from the main air stream.

Other objects and advantages will become apparent from the following description taken in connection with the accompanying drawings, in which:

Figure 1 is a fragmentary longitudinal sectional view of the front end portion of a turbo-jet engine embodying the features of the invention.

Fig. 1-A is a continuation of Fig. 1 and shows the intermediate portion of the engine.

Fig. 1-B is a continuation of Fig. 1-A and illustrates a still further portion of the invention.

Fig. 2 is a fragmentary transverse sectional view taken on the line 2—2 of Fig. 1.

Fig. 3 is a fragmentary transverse sectional view taken on the line 3—3 of Fig. 1-A.

Fig. 4 is another fragmentary transverse sectional view taken on the line 4—4 of Fig. 1-A.

In engines of the gas turbine type, the cooling of various parts of the apparatus, and particularly the turbine rotor, is an important factor because of the high temperatures of the combustion gases which drive the turbine. The high temperatures of these gases, of course, reduce the strengths of the materials of the various parts of the rotor at which they may safely operate. The materials utilized are selected from those which permit high operating stresses even at rela-

tively high temperatures. Nevertheless, even with such materials, the safe operating stresses thereof are lower than at reduced temperatures. Consequently, it is advisable to provide adequate cooling of the parts subjected to the heat of the combustion gases to obtain a maximum safe working stress. This is particularly true in connection with rotating parts since, obviously, by providing adequate cooling thereof, the mass of material may be reduced, thus reducing centrifugal stresses.

Merely by way of example, the temperature of the combustion gases contacting the blades of a turbine of this type may be as high as 1600° F., which temperature is so high that the metal should not be permitted to operate at such a temperature. Steel is the material commonly employed for the blades and other parts of the turbine rotor so that the actual operating temperature of the rotor and its parts should be maintained considerably below the temperature of the gases. Such cooling of the rotor parts may be accomplished by subjecting them to contact with a cooling fluid. Since air in large quantities is taken into an engine of this character to support the combustion, a portion of such air is utilized as the cooling fluid. Such air may be taken from the air stream provided to support combustion and, because of the heat absorbed thereby in cooling the rotor parts, it is preferably discharged into the power stream to minimize loss of efficiency of the engine.

In utilizing air from the main air stream created in the engine, consideration must be given, of course, to the pressure of such air so that it may discharge into the power stream at a sufficient pressure to effect such discharge. The pressure at which such air is withdrawn from the air stream, consequently, will depend upon whether or not any additional head is imparted thereto in cooling the parts of the turbine rotor. Thus, if no head is added to a cooling air stream when performing its cooling function, the air for such cooling stream should be withdrawn from the main air stream at the maximum pressure thereof so that it will have sufficient pressure to enter the power stream after performing its cooling function. If, however, any pumping action is exerted on a stream of cooling air in its passage through or around the turbine rotor, then such cooling air may be withdrawn from the main air stream at a point of lower pressure with the sum of the two pressures being sufficient to effect the eventual discharge of the cooling stream into the power stream. While, of course, the last-

mentioned cooling stream could be taken from the main air stream at a point of higher pressure, energy would be wasted in bringing the cooling air stream to such pressure if the ultimate pressure of the cooling stream were in excess of that needed to effect its discharge into the power stream. For that reason, it is desirable to withdraw any stream of cooling air from the main air stream at the point of minimum pressure necessary to effect its eventual discharge into the power stream with consideration given to any additional head that may be added to such cooling air stream.

The engine shown in the drawings and embodying the features of the present invention comprises an intake section 10 (see Fig. 1), in which is located air compressor means including an axial flow compressor 11 carried on a main drive shaft 12. The air stream created thereby flows through an annular passage 13 to a second compressor 14 of the combined axial and radial flow type, from which the air stream is discharged at its maximum pressure. From the compressor 14 the air stream passes through a collector 15 (see Fig. 1-A) and thence to combustion chamber means, indicated generally at 16. In the combustion chamber means 16, fuel is introduced into the air stream and combustion takes place to create the power stream for driving the turbine, indicated generally in Fig. 1-B at 17. After the power stream passes through the turbine 17, it, of course, is discharged through a tail spout, as indicated generally at 18. The compressor 14 is also mounted and driven by the shaft 12 which, in turn, is driven by the turbine 17.

In the present construction, the inlet 10, in which the compressor 11 is mounted, comprises a separate annular casting bolted to an intermediate compressor casing, indicated generally at 20, comprising an outer shell 21 and an inner shell 22 interconnected by a plurality of radially extending guide vanes 23. The compressor 14 is enclosed by a stationary casing 24 extending to and enclosing a portion of the collector 15. To stiffen the intermediate compressor casing 20, a plurality of hollow bulged portions 25 are provided thereon which form, with the wall 21 and the stationary casing 24, a rearwardly and outwardly extending passage 26.

The collector 15 includes collector vanes 30 (see Figs. 1-A and 3) which, at their forward ends, engage the rearward portion of the stationary casing 24 and are integrally formed with an outer shell portion 31 constituting a continuation of the stationary casing 24. At its front end, the outer shell 31 has a short cylindrical portion 32 and a flanged portion 33 which is bolted to a matching flange 34 on the intermediate compressor casing 20. At its rear end, the outer shell 31 is also provided with a flange 35, while the inner wall of the collector 15 extends rearwardly and tapers inwardly so that it may be rigidly secured as at 36 (see Fig. 1-A) to a main frame structure 37, in which the main drive shaft 12 is journaled.

The combustion chamber means 16 comprises an outer annular casing 40 and an inner casing 41. Mounted within the annular space between the inner and outer casings 40 and 41 is a plurality of combustion chamber members 42 arranged in circumferentially spaced relation to one another. The combustion chamber members 42, at their downstream ends, fit within an inner shell 43 which is spaced from the outer

casing 40 to provide an annular passage 44. Outside of the outer casing 40 is an outer shell 45 spaced from the outer casing 40 to provide another annular passage 46. The inner casing 41, at its upstream end, engages the collector 15 but tapers downstream at a different angle from the collector so as to provide an annular passage therewith, indicated at 47. The passage 47 continues downstream from the collector and its inner wall is provided by an inner shell 50 radially spaced from the wall 41, as is evident in Fig. 1-A.

Adjacent the turbine 17, the inner shell 50 is secured to a nozzle ring 51 (see Fig. 1-B) which supports a plurality of nozzle blades or vanes 52. The outer ends of the blades 52 are mounted in a supporting ring 53 constituting a continuation of the inner shell 43. The nozzle blades are hollow and, of course, direct the power stream from the combustion chamber means in proper relation to the blades of the turbine 17.

The outer casing 40 is secured to a turbine casing member 54 which provides, with the supporting ring 53, a continuation of the passage 44. Outside of the turbine casing member is a turbine shell 55 secured to and constituting a continuation of the outer shell 45 and providing with the turbine casing 54 a continuation of the passage 46.

The turbine 17 in the present instance is illustrated as a two-stage turbine comprising a rotor body 60 bolted to a flange 61 on the rear end of the main drive shaft 12. The rotor body 60 is provided with a pair of annular flange portions 62 which are axially spaced from one another and which respectively support turbine blades 63 constituting the first stage, and turbine blades 64 constituting the second stage. The turbine blades 63 and 64 are hollow and are open at their outer ends but are surrounded by a stationary shroud 65. Located between the two stages of turbine blades is a series of interstage guide vanes 66 supported at their outer ends by the turbine casing member 54 and extending inwardly through the shroud 65. The shroud 65, at its downstream end, is provided with a ring 70 which is shaped to meet the turbine shell 55, the latter extending downstream from the ring 70 and providing the tail spout. The interstage guide vanes 66, at their inner ends, support a hollow ring structure 71 positioned between the annular flange portions 62 of the rotor body 60.

To provide for suitable cooling of the various parts of the turbine, it is desirable to conduct a plurality of streams of cooling air respectively arranged to cool different parts of the turbine. In the present instance, three such streams are provided, one for cooling the upstream face portion of the turbine rotor 60, another for cooling the interstage facial portions of the turbine rotor, and the third for cooling the interior of the rotor and the two stages of the blades 63 and 64. The first two cooling streams are also arranged respectively to cool the nozzle vanes 52 and the interstage guide vanes 66. All of these streams of cooling air are eventually discharged into the power stream so that the energy therein is not completely lost.

The two streams of cooling air which are respectively used for cooling different facial portions of the turbine rotor are not subjected to any pumping action while performing their cooling function. Consequently, these two streams are withdrawn from the main air stream created by the compressors 11 and 14 at the maximum

pressure thereof so that there will be sufficient pressure in such cooling streams to effect their entrance into the power stream after performing their cooling function. The air stream utilized for cooling the interior of the turbine rotor and the two sets of blades 63 and 64 is subjected to a pumping action due to the rotation of the turbine rotor. Such pumping action, of course, will increase the pressure of this cooling stream and, consequently, the air therefor may be withdrawn from the main air stream at a point of lower pressure than exists at the discharge of the compressor 14.

The cooling air stream first referred to, which is adapted to cool the upstream facial portions of the turbine rotor 60, is withdrawn from the main air stream at points where such air stream passes between the combustion chamber members 42. To this end, the inner casing 41 (see Fig. 1-A) is provided with sets of apertures 80 and 81 to admit air from the main air stream into the upstream end of the passage 47. The cooling air is conducted downstream by this passage and at the downstream end of the passage it is permitted to enter a plurality of elbow-shaped tubes 82 (see Fig. 1-B) each having one end mounted in the nozzle ring 51. Mounted within the nozzle ring 51 is a casing having a cylindrical wall portion 83 and a radially extending wall 84. The walls 83 and 84 thus form an annular chamber with the nozzle ring 51. The elbow-shaped tubes 82 extend through the annular chamber just mentioned and have their other ends mounted in the radially extending wall 84 so that the air carried through such tubes is discharged onto the front face of the turbine rotor 60. Sheet metal nozzle members 55 are preferably formed over the ends of the tubes 82 so as to direct the air tangentially in the direction of rotation of the turbine rotor 60 whereby a minimum resistance to air flow is provided. The air thus discharged from the tubes 82 cools the front face of the turbine rotor 60 and flows outwardly into the power stream between the turbine rotor and the wall 84.

The stream of cooling air for cooling the inter-stage faces of the annular flange portions 62 is likewise withdrawn from the main air stream where it is substantially at its maximum pressure. Thus, air from the main air stream enters the annular passage 44 adjacent the combustion chamber members 42 and flows downstream to the space between the nozzle supporting ring 53 and the turbine casing member 54. At the downstream end of this space, there is a brace in the form of a ring 86 which, at its inner edge, supports the turbine shroud 65. The ring 86 is provided with a series of perforations 87 to permit the cooling air to flow therethrough, and such air continues to flow downstream in the space between the shroud 65 and the turbine casing member 54. The outer ends of the nozzle blades 52 are closed so that such air does not enter these blades.

As this cooling stream moves downstream between the shroud 65 and the turbine casing member 54, it passes around the outer end portions of the interstage guide vanes 66 and enters the space between the ring 70 and the outer shell 55. The cooling stream then reverses its flow to pass between the turbine casing member 54 and the outer shell 55 so that it may enter the outer ends of the hollow interstage guide vanes 66. The cooling air thus flows inwardly through these interstage guide vanes to maintain them

at a desirably low operating temperature. At the inner ends of the vanes 66, the cooling air enters the hollow ring structure 71 supporting the vanes 66. At its inner periphery, the hollow ring structure is provided with two series of apertures 90 opening toward the adjacent faces of the respective flange portions 62 of the rotor 60, and the air moves outwardly in contact with these flange portions at opposite sides of the ring structure 71 to discharge into the power stream.

Both of the streams of cooling air described in the foregoing are taken at a point in the main air stream which is substantially at the maximum pressure thereof. Both of these streams cool the external portions of the turbine rotor and no material amount of pumping action occurs in these two streams during their passage adjacent the rotor. The initial maximum pressure of these streams, however, is sufficient to cause their discharge into the power stream after effecting the desired cooling.

The third stream of cooling air utilized in the present construction is arranged to cool the interior of the rotor 60 as well as the two stages of turbine blades 63 and 64. However, as this cooling air passes through the turbine rotor and outwardly through the turbine blades, a pumping action is exerted thereon which increases the pressure thereof. Consequently, the pressure at which this stream of cooling air is received from the air compressor may be lower than the maximum thereof to substantially the extent that the pumping action of the rotor increases the pressure. In the present instance, it is found that the pressure of the main air stream at a point between the compressor 11 and the compressor 14 is sufficient, with the pumping action of the rotor, to effect the discharge of the air into the power stream.

To provide for this last-mentioned stream, the outer wall 21 of the intermediate compressor casing 20 (see Figs. 1 and 3) is provided with a plurality of apertures 91 opening into the passages 26 formed by the bulges 25 in the intermediate compressor casing. At the downstream end of the passages 26 are a series of openings 92 (see Figs. 1-A and 3) in the cylindrical portion 32 of the outer shell 31 of the collector 15. The flanges 33 and 35 of the collector 15 in line with the bulges 25 are provided with sheet-metal covers or plates 93 forming, with the outer shell 31 of the collector 15, continuations of the passages 26 so that the air taken from the passage 13 in the intermediate compressor casing 20 thus will flow through the spaces between the covers 93 and the collector 15. The flanges 35 of the collector are similarly provided with a series of apertures 94 (see Figs. 1-A and 4) to discharge this air into the passage 46 formed by the outer casing 40 and the outer shell 45 of the combustion chamber means.

At the downstream end of the passage 46 is a ring 95 which prevents the air from the passage 46 from entering the space between the turbine casing member 54 and the outer shell 55. The nozzle blades or vanes 52, however, are provided with expansion supports 96 (see Fig. 1-B) which are hollow, so that the air from the passage 46 may enter the interiors of the nozzle vanes 52. Cooling air is thus introduced into the nozzle vanes to maintain them at a sufficiently low operating temperature. It is to be noted that the expansion supports 96 are located adjacent the front edge of the nozzle blades 52, so that the maximum cooling effect

on the nozzle blades is produced at the front edge thereof, where the greatest amount of heat is received from the power stream emerging from the combustion chamber means.

The cooling air flowing inwardly through the nozzle vanes 52 enters the annular chamber formed by the nozzle ring 51 and the casing walls 83 and 84. The casing wall 83 is provided with a plurality of apertures 97 which permit this cooling air to enter the space immediately in front of the flange 61 which is formed on the downstream end of the main drive shaft 12 and supports the turbine rotor 60. From the space in front of the flange 61, the air is permitted to flow through a series of apertures 100 provided in the flange 61 to enter a central bore 101 in the turbine rotor 100. The downstream end of this bore is closed by a flange member 102 abutting the turbine rotor 60 and carried on an extension 103 secured to the main drive shaft 12. The extension 103 is substantially smaller than the diameter of the central bore 101 so that an annular space is thus provided within the turbine rotor to receive the cooling air entering through the apertures 100.

The interior of the turbine rotor 60 is provided with a pair of annular grooves 104 extending from the central bore 101, and from the grooves 104 extend in each of the flange portions 62 a series of radial passages 105. There are the same number of passages 105 as there are blades 63 and 64 and the passages are aligned with such blades and communicate with the interiors of the blades so that air from the central bore 101 will be discharged outwardly through the radial passages 104 and the blades 63 and 64. The air passing outwardly in this manner is discharged into the power stream at the outer ends of the turbine blades.

The rotation of the turbine rotor 60 with the blades 63 and 64 produces a pumping action on the air in the passages 105 and the blades, which increases the pressure of the air. Such pressure, when added to the pressure at which this stream of cooling air is withdrawn from the main air stream intermediate the two compressors, is sufficient to produce a total pressure at the outer ends of the turbine blades to cause the air to be discharged into the power stream. Because of the pumping action of the turbine rotor on this stream of air, the air is withdrawn from the power stream at a point below maximum pressure, and less energy is expended thereon than if it were withdrawn from the main air stream at a point of maximum pressure. The total pressure of the air at its point of discharge, however, is sufficient to effect its entrance into the power stream.

I claim:

1. An internal combustion gas turbine engine having at least two stages of air compressing means associated therewith comprising: a forwardly sloping generally conically shaped front housing; a first stage axial flow air compressor at the forward end of said housing; a second stage axial and radial flow compressor to the rear of said first stage compressor; an annular passage within said housing to conduct the partially compressed air from the first stage compressor to said second stage compressor; a compressed air collector ring at the discharge end of said second stage compressor, said ring forming a compressed air passage; an outer annular passage within said front housing, said outer annular passage surrounding said first named

annular passage as well as said second stage compressor and said air collector ring; the common wall between said two annular passages having ports therein to permit a portion of the partially compressed air to flow into the outer annular passage; a rearwardly sloping generally conically shaped rear housing; said rear housing having an annular air passage inside thereof that is substantially co-extensive with its inner wall and which defines a space within the rear housing; said outer annular passage in the front housing communicating with said co-extensive passage in the rear housing; a combustion chamber disposed rearwardly from said collector ring and within said space; a hollow bladed gas driven turbine having a rotor disposed within the rear portion of said rear housing; means to feed fuel to said combustion chamber; said collector ring feeding compressed air to the space inside of said co-extensive passage; generally concentrically arranged annular air flow passages within said space and surrounding said combustion chamber; concentric passages having infeed openings at their forward ends whereby separate portions of the compressed air issuing from said ring enters each of said concentric passages; auxiliary passage means cooperating with said concentric passages to deliver air from adjacent the rear ends thereof to cool the outside surfaces of said turbine blades; and other auxiliary passage means cooperating with said co-extensive passage to deliver air therefrom to the center of said turbine rotor so that the air may be pumped outwardly through the hollow blades of the turbine by their rotation.

2. An internal combustion gas turbine engine having at least two stages of air compressing means associated therewith comprising: a forwardly sloping generally conically shaped front housing; a first stage axial flow air compressor at the forward end of said housing; a second stage axial and radial flow compressor to the rear of said first stage compressor; an annular passage within said housing to conduct the partially compressed air from the first stage compressor to said second stage compressor; a compressed air collector ring at the discharge end of said second stage compressor, said ring forming a compressed air passage; an outer annular passage within said front housing, said outer annular passage surrounding said first named annular passage as well as said second stage compressor and said air collector ring; the common wall between said two annular passages having ports therein to permit a portion of the partially compressed air to flow into the outer annular passage; a rearwardly sloping generally conically shaped rear housing; said rear housing having an annular air passage inside thereof that is substantially co-extensive with its inner wall and which defines a space within the rear housing; said outer annular passage in the front housing communicating with said co-extensive passage in the rear housing; a combustion chamber disposed rearwardly from said collector ring and within said space; a two stage hollow bladed gas driven turbine having a rotor disposed within the rear portion of said rear housing; means to feed fuel to said combustion chamber; said collector ring feeding compressed air to the space inside of said co-extensive passage; generally concentrically arranged annular air flow passages within said space and surrounding said combustion chamber; the inner of said concentric passages having infeed openings for compressed air

at its forward end; auxiliary passage means co-operating with said inner concentric passage to deliver air from adjacent the rear end thereof to flow over the forward edges of the first stage turbine blades and then rearwardly to the exhaust of the engine; the other of said concentric passages having infeed openings for compressed air at its forward end; auxiliary passages co-operating with said other concentric passage to deliver air from adjacent the rear end thereof to be directed outwardly into the gas stream of the turbine from near the center of said rotor and along the rear edges of the blades of the first stage of the turbine and the front edges of the second stage of the turbine; and other auxiliary passage means cooperating with said co-extensive passage to deliver air therefrom to the center of said turbine rotor so that the air may be pumped outwardly through the hollow blades of the turbine by their rotation.

GEORGE F. WISLICENUS.
